(57) **CLAIM**

The ornamental design for an optical communication apparatus, as shown and described.

DESCRIPTION

FIG. 1 is a front elevation of an optical communication apparatus showing our new design;

FIG. 2 is a rear elevation thereof;

FIG. 3 is a top plan view thereof;

FIG. 4 is a bottom plan view thereof;

FIG. 5 is a right side elevation thereof;

FIG. 6 is a left side elevation thereof;

FIG. 7 is a perspective view of the design shown in FIGS. 1 through 6;

FIG. 8 is a front elevation thereof in an alternate position;

FIG. 9 is a back elevation thereof;

FIG. 10 is a top plan view thereof;

FIG. 11 is a bottom plan view thereof;

FIG. 12 is a right side elevation thereof;

FIG. 13 is a left side elevation thereof; and,

FIG. 14 is a perspective view thereof.
